UNITED STATES PATENT OFFICE.

EUGENE L. BROWN, JR., OF CHICAGO, ILLINOIS, ASSIGNOR TO R. E. SPENCER GEARE,
OF CHICAGO, ILLINOIS.

CHAIN GRATE.

Application filed January 10, 1920. Serial No. 350,583.

To all whom it may concern:

Be it known that I, EUGENE L. BROWN, Jr., a citizen of the United States, residing at Chicago, in the county of Cook and State of Illinois, have invented certain new and useful Improvements in Chain Grates, of which the following is a specification.

This invention relates to improvements in chain grates and has for its object to provide a new and improved mechanism of that type which may be readily assembled and in which individual grate bars may be readily removed and replaced.

Another object consists in the provision of a new and improved grate bar.

Another object consists in a new and improved form of grate bar supporting mechanism.

These and other objects will be more fully set forth and described in the following specification and shown in the accompanying drawings in which—

Figure 1 is an end elevation of a portion of a chain grate showing a pair of grate bars in assembled position.

Fig. 2 is a plan view of the same.

Fig. 3 is a plan view of two pairs of grate bars adjacent transverse series, one set being inclined as when rounding the sprocket wheel of the mechanism.

Fig. 4 is a plan view of one of the grate bars.

Fig. 5 is a side elevation of the same.

Fig. 6 is an end view of the same.

Fig. 7 is a section along the line 7—7 of Fig. 1.

Fig. 8 is a perspective of one of the locking keys.

Fig. 9 is a fragmentary view, partly in section of a chain grate constructed in accordance with the present invention, showing the same in its travel over one of the rear sprocket wheels.

Like numerals refer to like elements throughout the drawings, in which 10 indicates one of the links, of the drive chains which coact with the sprocket wheels, one of which is shown at 15. Each of these links 10 comprises rearwardly extending lugs 10^a and the forwardly projecting lug 10^b. These chain links are also provided with transversely extending flanges or lugs 10^c the inner walls thereof converging downwardly

to form a tapered seat, the lugs being transversely apertured, as indicated by numeral 10^d, these apertures being elongated as shown in Fig. 1, for example. Formed on the inner face of one of the flanges 10^c of each pair is the groove 10^e, for a purpose to be hereinafter described. Coacting with and extending between the chain links 10 are the transverse supporting bars 11, each of said bars being provided with a plurality of dovetail grooves 11^a, the side walls of which converge to form tapered seats. Cut or otherwise formed in each of the seats 11^a is a key-way 11^b, the bottom 11^c thereof being inclined slightly adjacent one end to form the edge or vertex 11^d, see Fig. 7.

Coacting with and carried by the transverse supporting bars 11 are the grate bars 12, each of said bars being provided with a central portion 12^a and relatively offset oppositely projecting arms 12^b, 12^c. The offset arms 12^b, 12^c are provided with inclined slots or grooves 12^d in the sides thereof to afford draft passages to the fuel supported upon the grate. Each of the grate bars 12 is provided on its under side with a tongue 12^e tapered as shown in Fig. 6, for example, and adapted to fit the seat 11^a being restrained from passing entirely through said seat by the tapered construction, as will be obvious. To lock and secure the grate bars to the supporting bars I provide keys 14, each of which is provided with upwardly extending shoulders 14^a, 14^b and downwardly extending shoulder 14^c. In the assembling of the grate these keys are seated in the key-ways preferably as shown in Fig. 2, for example. The tongue 12^e of the grate bar is then moved into its seat over the shoulder 14^b of the key, the inclined bottom portion of the key-way 11^b permitting tilting of the key 14 upon the edge 11^d until the bottom of the tongue 12^e strikes the body of the key 14 at some distance to the rear of shoulder 14^b. A sharp blow upon the bar 12 will then result in the bending of the key 14, which is preferably constructed of resilient metal, such as spring steel, about the edge 11^d, the sides of the seat 11^a preventing upward movement of the grate bar. As soon as the tongue 12^e has been driven over the shoulder 14^b of the key 14, the latter will

spring back to normal position, as shown

in Fig. 7, thereby locking the bar in its seated position, the shoulders 14^a , 14^b as well as the tapered construction of the seat 11^a and tongue 12^c preventing displacement 5 of the bars in one direction, while the shoulder 14^c will prevent movement of the bar in the other direction, as will be obvious. This construction enables ready assembly of the grate proper and should one of 10 the bars thereof become broken or its replacement become necessary for any other reason, it is merely necessary to wait until the grate in its travel over the sprocket wheels is such that the transverse series of grate bars which 15 includes the one to be removed is tilted, as indicated in Figs. 3 and 9; when a cold chisel or other tool may be inserted and the edge thereof placed against one end of the key 14 when a sharp blow thereon will either break 20 the key or bend the same sufficiently to permit removal of the broken link by sliding it off its seat, as will be apparent. While either end of the key may be broken or bent in this way, it is, of course, preferable to attack the shoulder 14^b as this will permit bending of the key about the edge 11^a and there is no shoulder on the under side to interfere with such bending.

It will be understood that the chain links 30 are provided with similar seats and key-ways to accommodate grate bars.

To guard against injury of the grate mechanism, should one of the transverse supporting bars 11 become broken, I construct the same with the ends thereof tapered, as indicated by numeral 11^b ; a rib or lug 11^c being formed on one side thereof to fit in the groove 10^e of chain link 10 , the supporting member being provided with a 40 transverse hole or aperture 11^k to aline with the apertures 10^d to permit driving of a fastening pin or the like therethrough. The ends 11^b of the supporting member 11 are tapered to provide a wedging fit with the 45 lugs 10^c , the elongated aperture 10^d in such lugs insuring alinement of the aperture 11^k therewith. Should one of the supporting members 11 break intermediate its extremities, the tapered construction at the end, together with the engagement of the rib or lug 11^c with the groove 10^e , it will prevent dropping of the broken end and thereby impairment of the stoker mechanism. The links 50 10 composing the side drive chains (see Fig. 55 9) obviously need only be provided with one pair of lugs 10^c , while the links of intermediate chains will have two pairs of lugs 10^c , one on each side thereof as shown in Figs. 1 and 2.

I have shown in Fig. 3 the offsetting of the arms 12^b , 12^c of the grate bars to permit the fitting therebetween of corresponding arms of adjacent sets of bars as will be readily understood by those skilled in the 60 art.

It will be apparent that my invention is susceptible of numerous modifications and improvements and I do not wish to be restricted to the form shown except as defined in the appended claims.

What I claim is:

1. In a chain grate, a supporting member, said supporting member having a tapered seat, a grate bar having a tapered portion engageable with said tapered seat, and spring means to lock said bar in seated position. 70

2. In a chain grate, a supporting member, said supporting member having a tapered seat, a grate bar having a tapered portion engageable with said tapered seat, and spring means to lock said bar in seated position, said last-named means comprising a 75

key. 80

3. In a chain grate, a supporting member, said supporting member having a tapered seat, a grate bar having a tapered portion engageable with said tapered seat, and means to lock said bar in seated position, said last-named means comprising a key of resilient material having portions engageable with said bar and said supporting member upon movement of the former into operative position. 85

4. In a traveling grate, a supporting member, said supporting member being provided with a tapered dovetail seat and a key-way, a grate bar having a tapered portion engageable with said seat, and means to prevent removal of said bar from seating position, said means comprising a key of resilient material located in said key-way and having a shoulder portion engageable with said bar and a portion engageable with said supporting member upon movement of said bar into 100 operative position. 100

5. In a chain grate, a chain link, a transverse supporting bar, said link being provided with spaced apart lugs, said supporting bar fitting between said lugs, said lugs and said bar being provided with an interfitting groove and lug, said chain link and supporting bar being provided with transverse alining apertures and fastening means 110

extending through the latter. 110

6. In a chain grate, a chain link, a transverse supporting bar, said link being provided with spaced apart lugs, said supporting bar fitting between said lugs, said lugs and said bar being provided with an interfitting groove and lug, said chain link and supporting bar being provided with transverse alining apertures and fastening means 120

extending through the latter, the aperture in 125

7. In a chain grate, a chain link, a transverse supporting bar, said link being provided with spaced apart lugs, said supporting bar fitting between said lugs, said lugs and said bar being provided with an interfitting groove and lug, said chain link and supporting bar being provided with transverse alining apertures and fastening means 130

said chain link being elongated to insure alignment with the aperture in said supporting member.

8. In a chain grate, a chain link having
5 spaced apart lugs, the adjacent surfaces of
said lugs converging downwardly to provide
a tapered space therebetween, a supporting
member having a tapered extremity fitting
in the space between said lugs, transverse
10 apertures extending through said member
and lugs, and fastening means extending
through the latter.

9. In a chain grate, a chain link having spaced apart lugs, the adjacent surfaces of said lugs converging downwardly to provide a tapered space therebetween, a supporting member having a tapered extremity fitting in the space between said lugs, one of said lugs being provided with a groove, said supporting member being provided 15 with a coacting lug to fit in said groove.

10. In testimony whereof, I have subscribed
my name.

EUGENE L. BROWN, JR.
